Primary Examiner — Jennifer L Rempfer*Assistant Examiner* — Edward P Jones(74) *Attorney, Agent, or Firm* — McAndrews Held & Malloy, Ltd.(57) **CLAIM**

The ornamental design for an analyte sensor device, as shown and described.

DESCRIPTION

FIG. 1 is a front perspective view of an analyte sensor device, with an applicator shown in broken lines to illustrate environment;

FIG. 2 is a right perspective view thereof;

FIG. 3 is a top plan view thereof;

FIG. 4 is a bottom plan view thereof;

FIG. 5 is a front elevation view thereof;

FIG. 6 is a left elevation view thereof;

FIG. 7 is a right elevation view thereof; and,

FIG. 8 is a rear elevation view thereof.

The dashed broken lines showing an applicator in FIG. 1 illustrate environment and form no part of the claimed design. The remaining dashed broken lines in the drawings illustrate portions of the analyte sensor device that form no part of the claimed design.
